UNITED STATES PATENT OFFICE.

ORRIN TABER, OF NASHUA, NEW HAMPSHIRE.

DESIGN FOR A FILLING-BLOCK FOR SADDLE-TREE SEATS.

SPECIFICATION forming part of Design No. 19,631, dated January 28, 1890.

Application filed December 30, 1889. Serial No. 335,406. Term of patent 14 years.

To all whom it may concern:

Be it known that I, ORRIN TABER, a citizen of the United States, residing at Nashua, in the county of Hillsborough, State of New

5 Hampshire, have invented and produced a new and original Design for Filling-Blocks for Saddle-Tree Seats, of which the following is a specification, reference being had to the accompanying drawings, forming part thereof.

10 Figure 1 is a plan view of a filling-block for saddle-tree seats showing my design; Fig. 2, an end view of the block shown in Fig. 1; Fig. 3, a side view of the block shown in Fig. 1, and Fig. 4 a sectional view.

15 The block is oval in shape, or nearly so, as shown in Fig. 1. It is made quite thick at one edge, as at 2, and tapers gradually to the opposite edge to thereby present a wedge-

shaped block, as best shown in Figs. 3 and 4. At the edge 2 and on the upper side of the 20 block a recess is formed, its depth being sufficient to leave shoulders 3 3.

I claim—

The design for a filling-block for saddle-tree seats herein shown and described, the 25 same consisting of an oval wedge-shaped block having a recess at the thickened edge of sufficient depth to present shoulders 2, as set forth.

In testimony whereof I have signed my 30 name to this specification in the presence of two subscribing witnesses.

ORRIN TABER.
